UNITED STATES PATENT OFFICE.

WILLIAM KAISER, OF WILKES-BARRE, PENNSYLVANIA.

MEANS FOR FASTENING HYDRANT-TOPS, &c.

SPECIFICATION forming part of Letters Patent No. 268,686, dated December 5, 1882.

Application filed April 6, 1882. (No model.)

To all whom it may concern:

Be it known that I, WILLIAM KAISER, a citizen of the United States of America, residing at Wilkes-Barre, in the county of Luzerne and State of Pennsylvania, have invented certain new and useful Improvements in Means for Fastening Hydrant-Tops, &c.; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to an improvement in means whereby the top or hood part is connected to the stock part of hydrants, pumps, &c., as hereinafter set forth.

In the drawings hereto annexed, Figure 1 20 is a vertical section, showing the hood and stock connected. Fig. 2 is a side view of the hood separately. Fig. 3 is a side view of the stock separately. Fig. 4 is a cross-section of the parts on the line xx in Fig. 1.

25 The letter A designates the hood; A', the top or cap to the hood. The hood is cylindrical and made of cast-iron.

B represents the stock of a hydrant or pump, and consists of a tube whose upper end fits 30 within the lower end of the hood. The hood stands in a vertical position, and upon the inner side of the wall and near the lower end the hood has a groove, c, which extends for a short distance in a horizontal direction around 35 the curved face of the wall. The shape of this groove in cross-section is half-round, as seen in Fig. 1. A hole, c', in the hood passes through the wall thereof in a direction tangential to the outer side of the cylinder, and leads into 40 the inside groove, c. On the side of the hood diametrically opposite the inside groove, c, a set-screw, d, enters and passes through the wall; but instead of the set-screw an equivalent device might be used, such as a cam-lever 45 working in a slot through the wall. The stock B is provided on its exterior, and near its upper end, with an annular groove, e, which in cross-section is of a half-round shape. A piece 50 of metal wire or round rod, F, is curved or segment-shaped, and is adapted to enter through

the hole c' in the hood. This, as hereinafter explained, serves as a key. The two parts are united by the lower end of the hood setting down over the end of the tube which has the annular groove on its exterior. The segment-shaped key F is then inserted endwise into the hole c' in the hood. This key will thereby take position partly in the groove e on the stock and partly in the groove c on the inside of the hood, as shown in Figs. 1 and 4. The set-screw d on the opposite side should then be turned until its end enters the annular groove e. When the set-screw is tightened it has the effect to draw the opposite side of the hood close against the stock, or close against the key F. The latter then by its position, partly in each of the grooves on the two parts, serves to secure the hood from removal. When it is so desired the removal of the hood or top is easily effected by simply turning the set-screw d, by which its end is withdrawn from the annular groove c. The key F may then be drawn out and the two parts separated. The set-screw d serves as a tightening device, as already explained; but any other device which will produce the same effect may be used instead of the set-screw.

The hole c' to enter the key may be dispensed with by forming on one of the parts a socket large enough to afford reception for the key, 80 in order that the said key may be placed therein previous to the parts being put together. By the socket being in connection with the grooves c and e, and the key being loosely in the socket, the key may, after the parts are 85 put together, be directed into its position between the two grooves by the jarring motion imparted to the parts by the tap of a hammer. While this means of fastening is shown applied to a hydrant, it is applicable to other devices, 90 such as pumps and other things where two parts are to be similarly connected. Furthermore, it is immaterial whether the lower end of one part sets down over the upper end of the other part, or whether the relative positions 95 are reversed—that is, the lower end of one part setting down inside of the upper end of the other part.

In the drawings, an inward shoulder, g, is shown extending around the inner side of the 100

wall of the hood, and a metal washer, *h*, is also shown between the said shoulder and the upper end of the stock. These features are useful in the case of a hydrant or similar device, but are not essential to the operation of the fastening means herein claimed.

The opening *i* in the wall of the hood is for the nozzle of the hydrant to project through.

Having described my invention, I claim and desire to secure by Letters Patent of the United States—

In a hydrant, the herein-described means of securing the top and stock together, consisting

of the combination of the top and stock, each having their adjacent surfaces provided with a groove, a key to fit the grooves, a hole through the wall of the one part to enter the said key, and a tightening device on the opposite side, as set forth.

In testimony whereof I affix my signature in presence of two witnesses.

WILLIAM KAISER.
